CLAIM

The ornamental design for a support for disc-like weights, as shown and described.

DESCRIPTION

FIG. 1 is a perspective view of the first embodiment of a support for disc-like weights, showing my new design; FIG. 2 is a left side elevation view thereof; FIG. 3 is a right side elevation view thereof; FIG. 4 is a front elevation view thereof; FIG. 5 is a rear elevation view thereof; FIG. 6 is a top plan view thereof; FIG. 7 is a bottom plan view thereof; FIG. 8 is a perspective view of the second embodiment of a support for disc-like weights thereof; FIG. 9 is a left side elevation view thereof; FIG. 10 is a right side elevation view thereof; FIG. 11 is a front elevation view thereof; FIG. 12 is a rear elevation view thereof; FIG. 13 is a top plan view thereof; and, FIG. 14 is a bottom plan view thereof.
The stippling in FIGS. 8–14 indicates a rough textured surface.

1 Claim, 10 Drawing Sheets
